UNITED STATES PATENT OFFICE.

FRANCIS E. MOORE, OF BOSTON, MASSACHUSETTS, ASSIGNOR TO EDWARD L. RAND, OF SAME PLACE.

KEY-BOARD ATTACHMENT FOR MUSICAL INSTRUMENTS.

SPECIFICATION forming part of Letters Patent No. 269,810, dated December 26, 1882.

Application filed March 30, 1882. (No model.)

To all whom it may concern:

Be it known that I, FRANCIS E. MOORE, of Boston, in the county of Suffolk and State of Massachusetts, have invented certain new and useful Improvements in Key-Board Attachments for Musical Instruments, of which the following is a full, clear, and exact description.

This invention relates to attachments for musical instruments having a key-board, adapted to be readily secured to or removed from the key-board, and constructed and arranged to mechanically strike the keys of the instrument, and thereby to sound the notes or tones thereof, in an order or succession corresponding to the perforations in parallel rows in a music-sheet, that is caused to travel in proper relation to the operating mechanism of the attachment.

The improvements will be fully hereinafter described in detail, and set forth in the claims.

In the accompanying drawings, illustrating my invention, Plate 1, Figure 1 is a plan view of the key-board of a reed-organ and of the improved attachment therefor, which in some parts is shown as broken away and in horizontal section, as will appear more fully hereinafter. Plate 2, Fig. 2 is a transverse vertical section. Fig. 3 is a longitudinal vertical section for a part of the length of the attachment. Fig. 4 is a detail view, hereinafter referred to. Fig. 5 is a transverse vertical section illustrating a modification, hereinafter fully described.

In the drawings, A represents a main case, composed of vertical end pieces, B B, and a horizontal top or platform, C; and D is a supplementary casing, surmounting the platform C, and attached to it in any suitable manner, but so as to leave an open slot, a, at its front and rear sides just above the platform. The cases A D carry within them the working parts of the attachment, as will be explained hereinafter, and the main case A has at each end piece, B, a hook-lug, b, Fig. 4, each adapted to be engaged with and disengaged from a recess, c, in a stationary block, E, at each end of the key-board of the musical instrument—such as an organ, melodeon, or piano-forte—for which the attachment is to be used, as a means of securing an automatic operation of the keys from the travel of and in accordance with the per-

forations of a music-sheet of paper or of other suitable material in proper relation to the operative mechanism of the attachment. The case A, when its hooks b are engaged with the recesses c of the blocks E, has a rest by the lower edge, d, of each of its end pieces, B B, upon a suitable block fixed at each end of the key-board, and which blocks may be in one piece with the blocks E or separate therefrom, but of course situated in such relation thereto as to secure the rest, and as a consequence the support of the case A, desired when the hooks b are engaged with the recesses c.

F is the music-sheet. This music-sheet is to be made of card-board, paper, cloth, or other suitable flexible material, and it has cut in it a series of parallel and equidistant rows of perforations, e, which perforations are of lengths and of a relative arrangement to represent the different notes of a tune, or of a chord, or of any other arrangement of musical tones. The music-sheet F may be of any desired length; but for its proper guidance through the attachment constituting this invention it preferably should have a width equal to the distance between the two parallel end standards, G G, which project above the platform C. The music-sheet travels over the platform C in and between the standards G G, which act as guides to it, in the direction represented by the arrows of the drawings, and its said travel is secured by means of a horizontal feed-roller, H, arranged to turn at each end in bearings of the standards G G, and by flanges h to closely press and confine the music-sheet F to the upper surface of the platform C at and between the series of holes f in it. These holes f are at equal distances apart, and they severally correspond in position to the rows of perforations e in the music-sheet, and the feed-roller H has in corresponding lines therewith a series of parallel peripheral grooves, g, each of an equal depth, and such as to admit of the desired projection of levers or jacks J through the perforations e of the music-sheet F and into them, as will hereinafter fully appear. The feed-roller H, between its peripheral grooves g—that is, at its flanges or portions h, which bear upon the

music-sheet—is covered with rubber or other yielding or elastic material, and preferably one—such as rubber—as will secure a friction and hold upon the music-sheet to insure its feed or travel over the platform as the feed-roller is turned.

K and L are two gear-wheels of different diameters, secured to the journal m at one end of the feed-roller H. The inner gear-wheel, 10 K, is of a larger diameter than the outer gear-wheel, L, and the two are separated from each other, as shown.

M is a horizontal shaft located below the platform C, and arranged to turn at each end 15 in suitable bearing in one end B of the case A and in one of the uprights G for the feed-roller H. The feed-roller H and horizontal shaft M are axially in the same vertical plane, and the latter is provided with two gear-wheels, 20 O and P, of different diameters, separated from each other, but attached to or a part of a common sleeve, Q, which surrounds the shaft M, and is connected thereto by a longitudinal spline-joint, so as to be free to slide length- 25 wise thereon, and at the same time to rotate and turn with the shaft when it is turned. The smaller gear-wheel, O, of the shaft M is the inner one of the two, and its diameter is such as to engage with the inner and larger gear-wheel, 30 K, of the feed-roller H, and the diameter of the outer and larger gear-wheel, P, of the shaft M is such as to engage with the outer and smaller gear-wheel, L, of the feed-roller. The gear-wheels O P of the shaft M are situated so 35 that when one, O, is engaged with its gear-wheel K of the feed-roller the other, P, will be disengaged from its gear-wheel L thereof, and vice versa. This respective engagement and disengagement is secured by a slide of the 40 gear-wheels O P and their carrying-sleeve Q along their shaft, and for so sliding them a lever, R, is provided. This lever R, by its forked end r, partially surrounds the sleeve Q, and it turns upon a fulcrum at s of the case 45 A. The lever projects, for convenience of operating it, by its end t through a slot, u, at the front side of the case A, as it (the case) is located upon the musical instrument, and the end walls of this slot limit the throw of the lever 50 in either direction, and are situated so as to secure the relative engagement and disengagement of the gear mechanism above described.

S is a worm gear-wheel secured to the shaft M, and meshing with a worm gear-wheel, T, of 55 a horizontal shaft, U, arranged to turn in suitable bearings of the case A, and to be driven by a hand-crank or winch attached to it at the front side of the case, or by any other suitable means. The turning of the driving-shaft U 60 secures, through the connecting mechanism described, the turning of the feed-roller, and, according as either the large or the smaller gear-wheel of the shaft M is meshed with its gear-wheel of the feed-roller, the feed-roller will be 65 driven with a greater or lesser degree of rapidity.

There is a lever or jack J for each row of perforations e in the music-sheet, and each lever at its part for projection through a perforation of the music-sheet and into a groove 70 g of the feed-roller, as has been stated, has a wedge-shaped projection, v. Each lever or jack J is arranged within a separate guideway or groove, l, of the horizontal platform C of the case A, and they are severally horizontal, and they project toward the front of the case, and are arranged to turn upon a separate fulcrum-pin, w, which preferably are severally of a continuous wire, located and secured in a suitable position therefor.

Under the platform are horizontally arranged hammer-levers W—one for each of the jack-levers. Each hammer-lever W at one end is provided with an adjustable tappet or button-head, x, by which to rest upon a key, X, of the 85 key-board of the musical instrument, and otherwise each is arranged to swing in a vertical plane upon a suitable fulcrum, and to be given a spring-pressure in a downward direction upon its proper key of the instrument. Each 90 hammer-lever W has a separate fulcrum, f², of a common horizontal rail, C², and its downward spring-pressure is secured by giving the lever itself a bent form and springy character, and attaching it to the rail C², which attachment makes its fulcrum, as aforesaid. Each 95 spring hammer-lever W passes through a separate guide-slot, g², of a common stationary rail, O², and the rail C², to which they are severally attached, is hinged to the upper side of 100 a stationary horizontal rail, F², of the case, and it is arranged to be swung thereon and adjusted by a thumb set-screw or set-screws, h², to give a greater or lesser degree of spring-pressure to the hammer-levers, as may be desired. The turning of the thumb-screw h² in one direction swings the rail C² in a manner to secure a stiffening of the spring-pressure of the spring hammer-levers, and the turning of it in the other direction operates the reverse, and 105 thus the spring-pressure of the hammer-levers can be adjusted. Each hammer-lever W is connected with a jack-lever J, and such jack-lever, as to its row of perforations in the music-sheet, agrees with the relative position of 110 its key X in the scale of the key-board, upon which said hammer-lever rests. Therefore, as is obvious, for a proper relative arrangement of hammer-levers and jack-levers as to the 115 keys of the key-board and the rows of perforations in the music-sheet, if the music-sheet and the guiding and feeding mechanism therefor be constructed and arranged for a music-sheet of a width narrower than the width occupied by the several keys of the key-board of 120 the instrument, either the hammer-levers or the jack-levers, or the connecting mechanism between the two sets of levers, or two or more of such separate contrivances, must of necessity 125 run in lines more or less diverging from each other, and from the central line of the attachment, where all such contrivances, as a whole, 130

for the key, are coincident with such central line and with the key of the key-board, and this divergence of the contrivances, as is obvious, will be uniform and regular upon each side of the central line of the attachment, if the attachment be arranged for the feed-roller to operate on the music-sheet, so that the central line of the music-sheet travels in a line coincident with the line of the central key of the key-board.

The jack-levers J and the hammer-levers W are in lines parallel with each other and with the lines of the keys X, and the mechanism which makes the connection between the jack and hammer levers runs in each instance in a diverging line at and from each side of the central hammer-lever and jack-lever, which levers, together with the connecting mechanism, are in a coincident vertical plane. Each jack-lever is of an angular shape. Its fulcrum is at its angle, and the lower vertical arm, n^2 , of the lever is connected by a wire, q^2 , or other flexible rod to the upper vertical arm, r^2 , of an angular lever, H^2 , which has its fulcrum s^2 in a lug, t^2 , and at its other arm, u^2 , is connected by a rod, v^2 , to the outer end of the proper hammer-lever W for such jack-lever. As a hammer-lever and its jack-lever necessarily are not in the same vertical plane, except as to the central hammer-lever and its jack-lever, and as the jack-levers and hammer-levers are, however, arranged in parallel lines with each other, the mechanism above described as connecting a jack and a hammer lever necessarily must run in one, if not more, of its parts diagonally with the parallel arrangement of the jack and hammer levers, except it is the central hammer-lever and jack-lever.

As arranged, the wire connections and angular levers run diagonally as above stated, and in order to secure an action between the wire connections and the jack-levers in a direct line with the jack-levers each wire connection, except that of the central hammer and jack levers, runs about and has a bearing against a separate and vertical roller, w^2 , which are severally attached to a common horizontal rail, J^2 , of the case A, and suitably located to secure the direct action stated.

The arrangement of the jack and hammer levers and the connection between them, as above described, is all such that the depression of the free end m^2 of a jack-lever—that is, the end thereof located to pass into and out of a perforation in the music-sheet and a groove of the feed-roller—will operate upon the hammer-lever of such jack-lever in a direction to raise the outer end of said hammer-lever against its spring-pressure, and so that the free end m^2 of the jack-lever will rise and the outer end of the hammer-lever fall when the force applied to depress the jack-lever is removed.

In the arrangement of hammer-levers and jack-levers above described, together with the construction and arrangement of feed-roller

and other parts previously described, the music-sheet is caused to move over the platform C under the feed-roller, and as the solid or unperforated portions of the music-sheet come into contact with the jack-levers the jack-levers are depressed to a distance corresponding to the depths of the grooves in the feed-roller H and to the thickness of the material composing the music-sheet, and the outer ends of the hammer-levers are lifted a sufficient distance in relation to the keys for the keys to resume their normal position of rest and be maintained in such position until perforations of the music-sheet come into position with the jack-levers, when the corresponding hammer-levers are freed to the action of their springs, and they then act upon their keys and depress them, and thus secure the sounding of the notes belonging thereto, and so the parts remain until another solid or unperforated portion of the music-sheet comes into contact with the jack-levers, when the raising of the hammer-levers again takes place and the keys come to a normal position of rest, and so on, as before.

It is apparent from the description given that the throw of the hammer-levers is not dependent upon the thickness of the music-sheet, but has increased length given to it because of the grooves g in the feed-roller, whereby comparatively thin material for the music-sheet may be used without practically affecting the correct operation of the attachment.

Mechanism other than the roller H, which has been herein particularly described as the feed-roller, may be employed for feeding the music-sheet forward through the attachment without depending on the roller H as the feed, in which case the roller could be made stationary, and be made simply a bar with grooves g in its face toward the jack-levers.

In Fig. 5 the mechanism shown as the connection between each of the hammer and jack levers consists in a horizontal extension, P^2 , of the lever H^2 , and the jack-lever rests and operates upon this extension through a vertical pin, a^2 , arranged in a suitable guideway, b^2 . This extension P^2 of the lever H^2 is in place of the flexible wire q^2 and of the guide-roll w^2 for such wire, and the vertical pin a^2 is in place of the downward-projecting arm of the jack-lever J, as previously shown and described; but plainly the construction and operation are in both cases substantially and practically similar.

In Figs. 2 and 5 are shown arrangements of devices for lifting and holding the hammer-levers out of their operative position, more particularly when the attachment herein described is to be placed into and out of its position upon the musical instrument, and when a music-sheet is to be inserted. These mechanisms consist of a horizontal angular rail, K^2 , fulcrumed at its angle, and adapted by one arm, d^2 , to operate against and upon the connecting mechanism between the jack and hammer

levers, and by the other arm, c^2 , to be operated from a cam-lever, L^2 , of suitable shape to throw the lever-rail K^2 in a direction to secure the lifting of the hammer-levers against their springs and hold them so lifted, and for said rail K^2 to be freed from the hammer-levers.

As shown in Fig. 2, the lever-rail K^2 is arranged to work upon the lower projecting arm, n^2 , of the jack levers, whereas in Fig. 5 it is arranged to work upon the extension P^2 of the connecting-lever H^2 . However, both are substantially alike.

The hammer-levers W may have the spring-pressure required upon them given to them by springs which are separate and distinct from them.

The herein-described arrangement of gear mechanism for driving the feed-roller enables the attachment to be readily changed for a travel of the music-sheet at a greater or lesser rapidity with a given number of turns of the crank-handle in each case, the advantages of which are obvious.

In the combination of the attachment with a reed-organ, in order to facilitate the drawing of the stops to the organ, the attachment is provided with a suitable number of draw-rods, N^2 , one only being shown. This draw-rod N^2 passes through the case from front to rear, (see Fig. 2,) has a knob, y^2 , at its front end for convenience in operating it, and at its rear or inner end has two curved spring-arms, z^2 , shaped at their outer ends to engage with sockets a^3 in the opposite sides of a stop-knob, O^2 , and in their length to practically surround the stop-knob O^2 , and to be held in the engagement described through the spring given to the arms, which obviously allows them to be readily detached. The construction and arrangement of a draw-rod N^2 obviously enable

the organ-stop to which it is connected to be drawn or returned from the front of the case when the attachment is otherwise in operation.

Having thus described my invention, what I claim, and desire to secure by Letters Patent, is—

1. In a mechanical apparatus constructed to be attached to the key-board of a musical instrument, the combination of jack-levers J , hammer-levers W , connected together by levers H , and cords q^2 , with platform C and feed mechanism, all constructed and arranged together, and for operation in connection with a perforated music-sheet and the keys of the instrument, substantially as described, for the purpose specified.

2. Hammer-levers W , having the spring-acting portion of them secured to a rail, which is hinged and adapted to be adjusted in position, all so as to regulate the spring-pressure of the hammer-levers, substantially as described.

3. Hammer-levers W , in combination with a hinged rail, K^2 , having two arms, one of which is arranged to act upon the levers W by the operation of a cam-lever, M^2 , upon its other arm, substantially as described.

4. The slide draw-rod N^2 , having spring-springers z^2 , in combination with the organ-stop O^2 , and with an attachment to the key-boards of musical instruments substantially such as herein described, and all substantially as described, for the purpose specified.

In testimony whereof I have hereunto set my hand in the presence of two subscribing witnesses.

FRANCIS E. MOORE.
